Application July 5, 1952, Serial No. 297,306

Claims priority, application Netherlands July 17, 1951

4 Claims. (Cl. 313—346)

This invention relates to an incandescent cathode and more particularly to a cathode containing a supply of an alkaline earth compound capable of reduction by a refractory metal to free alkaline earth metal.

Cathodes of the aforesaid type have been described in U. S. Patent 2,543,728 to H. J. Lemmens et al. In the cathodes described in the patent, a reservoir of alkaline-earth compounds is located within a cavity of a body of refractory material which body has a porous wall portion and is tightly closed so that the pores of the porous wall portion form the largest connecting passageways connecting the reservoir of alkaline earth compounds with the outside of the cathode. The alkaline earth compounds disclosed in the said patent are the carbonates of the alkaline earth metals, for example barium and strontium which decompose at elevated temperatures to form the oxides of the alkaline earth metals with release of carbon dioxide. The latter must then be pumped off continuously to maintain a high vacuum in the tube.

It is an object of the present invention to eliminate the need for continuous evacuation of the discharge tube during activation of the cathode in an electric discharge tube.

This and further objects of this invention will appear as the specification progresses.

In accordance with this invention, the cathode comprises a structure forming an internal cavity, the portion of the structure surrounding the cavity consisting of a refractory metal such as tungsten, molybdenum, tantalum, zirconium or hafnium. Within the cavity a supply of an alkaline earth boride, for example, BaB₆ or SrB₆, and mixtures of those compounds is disposed. The cavity is sealed by means of a wall of porous refractory metal, the pores of this wall forming the largest passageways connecting the cavity to the exterior of the cathode.

The porous wall of the cavity preferably consists of a body of tungsten formed by pressing powdered tungsten and sintering the same at temperatures exceeding 1600° C. in order to obtain tungsten body of required porosity. As the borides do not require a high formation temperature such as carbonates the tungsten may be sintered as low as 1400° C. However, therein very fine powder should be used.

The borides of the alkaline earth metals should be preferably in a crystalline state.

Since there is no carbon dioxide formed during the life of the cathode, no exhaust of gas is required. The amount of gas released by a cathode of this type does not exceed the amount of gas liberated by other parts

2

of the tube and consequently, the cathode only requires a few minutes for the formation of a monomolecular layer of alkaline earth metal on the exterior surface.

The invention will be described in connection with the accompanying drawing in which the sole figure shows one embodiment of a cathode according to the invention.

The cathode shown in the drawing comprises a porous tungsten plate 1 formed as described in U. S. Patent 2,543,728 in order to have the correct porosity. The plate 10 is 0.5 mm. thick and 3 mms. in diameter. The tungsten plate 1 together with a cup-shaped molybdenum member 2 with a sharp upper edge 3 to which the tungsten plate is secured forms an internal cavity in which a supply 4 of about 1 to 5 mgs. of barium boride is disposed. 15 Plate 1 is welded to the edge 3 to tightly seal the cavity. The cathode is heated by means of a heater 5 disposed within a tubular extension 6 of the cup-shaped molybdenum member.

While the invention has been disclosed in connection with a specific embodiment thereof other modifications will be readily apparent to those skilled in this art without departing from the spirit and scope of this invention as defined in the appended claims.

What we claim is:

25 1. A dispenser cathode comprising a structure forming an internal cavity and having an electron emissive surface, a porous sintered body of refractory metal forming part of the wall of said structure, said structure being tightly closed with the pores of said wall portion constituting the largest passageways connecting the cavity to said electron emissive surface, and a supply within said cavity of an alkaline earth material capable of furnishing free alkaline earth metal to said electron-emissive surface at a rate sufficient to maintain a monomolecular layer 35 of alkaline earth metal thereon, said material consisting essentially of an alkaline earth boride.

2. A dispenser cathode comprising a structure forming an internal cavity and having an electron emissive surface, a porous sintered body of tungsten forming part 40 of the wall of said structure, said structure being tightly closed with the pores of said wall portion constituting the largest passageways connecting said cavity to said electron-emissive surface, and a supply within said cavity of an alkaline earth material capable of furnishing free alkaline earth metal to said surface at a rate sufficient to maintain a monomolecular layer of alkaline earth metal thereon, said material consisting essentially of an alkaline earth boride.

3. A dispenser cathode as claimed in claim 2 in which the alkaline earth material consists essentially of barium boride.

4. A dispenser cathode as claimed in claim 1 in which the alkaline earth material is a mixture of barium boride and strontium boride.
